UNITED STATES PATENT OFFICE.

PETER BROADBOOKS, OF BATAVIA, NEW YORK.

VEHICLE-BOW SUPPORT AND FASTENER.

1,250,789.

Specification of Letters Patent. Patented Dec. 18, 1917.

Application filed December 29, 1916. Serial No. 139,456.

To all whom it may concern:

Be it known that I, PETER BROADBOOKS, a citizen of the United States, residing at Batavia, in the county of Genesee and State of New York, have invented a new and useful Improvement in Vehicle-Bow Supports and Fasteners, of which the following is a specification.

This invention relates to bow supports and fasteners, such as are employed on automobiles, for clamping or firmly holding the bows when the top is folded. Devices for this purpose of various different constructions have heretofore been used in which the device is secured on the side of the vehicle body in position to support and hold the bows when the top is folded. These constructions are objectionable because they project out from the side of the body to such an extent as to be dangerous on account of the possible contact of the same with persons and objects, and when the top is raised or extended the support and fastener is conspicuous and detracts from the neat appearance of the vehicle. A bow support and fastener has also been heretofore used in which the clamping or fastening part is carried by one of the bows of the top, but this device also necessitates a stationary bow prop on the vehicle body which is large and projects out from the body so far as to be objectionable for the same reasons as the other constructions.

The objects of this invention are to overcome the objections mentioned and produce a practical and desirable bow support and fastener, adapted to be readily operated to securely fasten the bows when the top is folded and in which the prop or supporting member, as well as the clamping or fastening means of the device, is carried by the bows so that when the top is raised or extended both parts move therewith and no prop or support is left on the body which detracts from the neat appearance of the vehicle or projects far enough from the body to be objectionable.

With this end in view the combined bow support and fastener comprises a bow-supporting prop which is attached to one of the bows of the top and is adapted, when the top is folded, to be releasably secured stationarily to the vehicle body, and clamping

or fastening means which are also carried by and move with one of the bows and co-operate with the prop when the top is folded, for clamping or fastening the bows in place. Preferably the parts are pivotally mounted on the bow or bows by which they are carried, so that when the prop is detached from the body the parts can be placed lengthwise of the bow or bows and there secured to render the device less conspicuous.

In the accompanying drawings, bow supports and fasteners of different constructions embodying the invention are illustrated.

Figure 1 is a side elevation, on a reduced scale, of a bow support and fastener embodying the invention applied to the bows of a folded vehicle top, the top covering being omitted for the sake of clearness.

Fig. 2 is a transverse sectional elevation, on an enlarged scale, showing the device illustrated in Fig. 1.

Fig. 3 is a side elevation, enlarged, of the fastening means of the support and fastener detached from the bow.

Fig. 4 is a plan view of the device for releasably attaching the prop or supporting member to the vehicle body.

Fig. 5 is a fragmentary plan view showing the prop fastened in position lengthwise of the rear bow.

Fig. 6 is a transverse sectional elevation, similar to Fig. 2, showing a modified construction of the bow support and fastener.

Fig. 7 is a plan view showing the support and fastener illustrated in Fig. 6 disconnected from the body and secured to the rear bow lengthwise thereof.

Fig. 8 is a sectional elevation on line 8—8, Fig. 7.

Fig. 9 is a transverse sectional elevation showing another modification of the prop and stationary support of the device.

Fig. 10 is an elevation of modified means for releasably attaching the prop to the vehicle body.

A, Fig. 1 represents the rear or lower bow of a vehicle body, and B the front or upper bow. The folding bow construction illustrated in Fig. 1 is selected simply to show the application of the bow support and fastener thereto, it being understood that the device is applicable to other top constructions for

drawing or clamping the bows together and securing them to the body or stationary support so as to support and firmly hold the bows in place when the top is folded.

Referring first to the construction shown in Figs. 1 to 5, the combined bow support and fastener comprises a prop or supporting member 11 which is pivotally secured to and carried by the rear bow A, and fastening or clamping means 12 which are pivotally mounted on and carried by the front bow B and coöperate with the prop 11 or the rear bow A, when the top is folded, for clamping the bows. The prop 11 can be pivotally mounted on the bow A in any suitable way. As shown, it is pivoted at the inner side of the bow on a stud 13 on a sleeve or clip 14 secured on the bow. The clip is provided at the outer side of the bow with a hooked projection or stud 15 for the engagement of the clamping member of the device. The prop 11 is adapted, when the top is folded, to be releasably attached to and stationarily supported by an arm or support 16 which is secured to and projects a short distance only from the body of the vehicle. This support and the coöperating part of the prop 11 may be of any suitable construction adapting the prop to be quickly and easily secured to and released from the support. As shown, the support 16 is provided with an upright swivel post 17 having a crank handle 18 and the laterally projecting upper end of the prop 11 has a slotted opening 19, see Fig. 4, adapted to receive the swivel post and its handle 18. When the post is turned to the position shown in Fig. 2, the prop can be slid vertically onto and off of the post, the handle 18 being then adapted to pass through the slot 19 in the prop. The prop is secured by turning the post to a position, such as shown in Fig. 4, in which the handle of the post overhangs the upper end of the prop at one side of the slot 19 therein, thereby preventing the disengagement of the prop from the support or arm 16. A yielding washer 20 encircling the post 17 is compressed slightly when securing the prop and serves to hold the parts firmly and prevent rattling. Any other suitable means could be employed for releasably securing the prop 11 to the vehicle body. For instance, the upper end of the prop can be secured by a cotter pin or the like 21 on a fixed stud or post projecting from the support or arm 16^a, as shown in Fig. 6, or a cam lever and link fastening 22 could be employed for releasably securing the upper end of the prop on the arm or support 16^b, as shown in Fig. 10.

The fastening or clamping means of the combined support and fastener in the construction shown in Figs. 1 to 5 is suitably pivoted on the front bow B and comprises an eye or loop 23 adapted to engage the hook 15 on the rear bow, a clamping lever 24 piv-

oted to the loop and to a yoke 25, and a screw 26 having a threaded portion screwed into a threaded hole in the yoke 25 and an oppositely threaded portion screwed into a swivel post 27 which is swiveled in a socket 28 on a sleeve or clip 29 rigidly secured on the front bow. The socket can be secured on the bow and the post swiveled therein in any suitable way. By engaging the loop or eye 23 with the hooked stud 15 and forcing the lever 24 inwardly, the front and rear bows are drawn together, thus clamping the bows together and holding them firmly. The right and left-hand threaded screw 26 enables the clamping means to be lengthened or shortened as may be necessary to insure the proper clamping action. When the top is to be raised or extended the loop or eye 23 is disengaged from the hook or stud 15 on the rear bow and the clamping member can then be swung around on its pivotal connection with the front bow to a position lengthwise of the bow and there secured by engaging the loop or eye with a stud or projection 30 on the front bow, see Fig. 1, and operating the lever as when securing the clamp to the stud 15 on the rear bow. The prop 11 can then be released from the arm or support 16 on the body so as to be carried up with the bow A when the top is raised or extended. When the prop is disconnected from the arm or support 16 it is preferably swung to a position lengthwise of the rear bow and there secured, the rear bow being provided with means of any suitable construction for securing the prop in this position. For instance, the free end of the prop can be engaged with a lug 31, Fig. 5, fixed on the bow and having a seat in its outer end into which the prop is adapted to be snapped.

In the construction shown in Figs. 6, 7 and 8, the proper supporting member 11^a is pivotally mounted on the rear bow as above described and is adapted to be releasably attached to a stationary arm or support 16^a on the vehicle body as before described, or in any other suitable manner. In this construction the clamp or fastening part of the device, instead of being mounted on the front bow, as before described, consists of a screw which is carried by the prop 11^a and is adapted to be releasably engaged with the front bow B. This screw has right and left-hand threaded portions, one of which screws into a threaded hole in the free end of the prop 11^a, and the other of which works in a threaded hole in a block 32 which is provided with a stud 33 adapted to enter a socket 34 secured on the front bow B. When the stud is moved into the socket and the screw turned to move the block 32 toward the prop 11^a, the stud will be retained in the socket and the bows drawn together so as to securely clamp or hold

them in place. By providing the screw with right and left-hand threaded portions as described, its action in clamping and releasing the parts is much quicker. The stud 5 33 and socket 34 can be of any suitable construction adapted to permit the stud to be readily inserted into and removed from the socket and retained in place therein by the clamping action of the screw, and the socket 10 can be secured on the bow in any suitable way, or the block 32 could be releasably engaged with the front bow in any other suitable manner. As shown, the stud is adapted to move sidewise into the socket through an 15 opening in the side of the latter. When the stud 33 is released from the socket on the front bow, the prop 11^a can be detached from the arm or support 16^a to permit the raising of the top. The prop 11^a with the 20 clamping means carried thereby can then be swung around to a position lengthwise of the rear bow A and secured in this position by inserting the stud 33 in a socket 35 on the rear bow similar to the socket 34 on the 25 front bow. The stud is secured in this socket by operating the screw in the same manner that the stud is secured in the socket on the front bow. In this construction the fastening and supporting device, 30 comprising both the prop 11^a and the clamping screw or means, is carried by the rear bow, but the device including the prop and the clamping means is carried by and moves with the top when the top is raised, as in 35 the first construction described, and only the short arm or support 16^a is left projecting from the side of the vehicle when the top is raised. Also, as in the first construction, the fastening device, when the top is raised, is 40 retained in a position lengthwise of one of the bows, being thus practically hidden from view.

Fig. 9 shows a construction in which the bow-supporting prop 11^b is secured rigidly 45 to the rear bow, instead of pivotally. This prop is adapted for use with fastening means 12, such as shown in Figs. 1 to 3, and a hook 15^b is provided for the engagement of the fastener loop. The prop and hook 50 are shown as being made in one integral piece. As this prop can not be swung from the position in which it projects laterally from the bow, it is preferably made shorter than in the other constructions and coöperates with a stationary arm or support 12^b located lower down on the vehicle body. This rigid prop can be of different forms, as indicated for instance by the full and dotted lines in Fig. 9. It can be releasably attached to the arm 12^b as shown in Fig. 9, or by securing devices such as before described, or by any other suitable means.

37 and 38, Figs. 1 and 6, indicate inter-fitting studs and sockets or other suitable 65 coöperating parts on the bows, such as

commonly employed for holding the bows in place one vertically over the other. These can be used or not as desired.

I claim as my invention:

1. In combination with the bows of a 70 folding vehicle top, a bow support and fastener comprising a bow-supporting prop and coöperating bow-fastening means both carried by and movable with the top and movable relatively to each other for fastening the bows when the top is folded, said prop extending from the bows toward the vehicle body for attachment thereto, and means for releasably securing said prop to the vehicle body for supporting the folded 80 top, said prop when detached from the vehicle body being retained on the top. 75

2. In combination with a vehicle body and the bows of a folding vehicle top, a 85 bow support and fastener comprising a bow-supporting prop mounted on one of the bows and bow-fastening means which co-operate with another bow and with said prop for fastening the bows when the top is folded, said prop extending from the bows toward the vehicle body for attachment thereto, both said prop and fastening means being mounted on the top and retained thereon when the top is raised, and means for releasably attaching said prop to the 90 vehicle body for supporting the bows when the top is folded. 95

3. In combination with the bows of a 100 folding vehicle top, a bow support and fastener comprising a bow-supporting prop and coöperating bow fastening means which are movable relative to the prop for fastening the bows when the top is folded, means which connect said prop and fastening means with the bows for holding the bows 105 in folded position and which retain both the prop and the fastening means on the bows when the top is raised, said prop extending from the bows toward the vehicle body for attachment thereto, and means for releasably securing said prop to the vehicle body for supporting the folded top. 110

4. In combination with the bows of a 115 folding top, a bow support and fastener comprising a bow-supporting prop which is pivotally mounted on one of said bows to swing to and from a position lengthwise thereof and is retained on said bow, means for releasably holding the prop in said position, a stationary support, means for releasably securing the prop to said stationary support for supporting the top when folded, and fastening means carried by and retained on one of the bows and coöperating with another bow for fastening the bows when 120 the top is folded. 125

5. In combination with the bows of a 130 folding top, a bow support and fastener comprising a bow-supporting prop which is pivotally mounted on one of said bows to

- swing to and from a position lengthwise thereof, means for releasably holding the prop in this position, a stationary support, means for releasably securing the prop to 5 said stationary support for supporting the folded top, and fastening means which co-operate with another bow and with said prop for fastening the bows when the top is folded.
- 10 6. In combination with the bows of a folding top, a bow support and fastener comprising a bow-supporting prop which is pivotally attached to one of said bows to swing to and from a position lengthwise thereof, means for releasably holding the prop in said position, a stationary support, and means for releasably attaching the prop to said support for supporting the top when folded.
- 20 7. In combination with the bows of a folding top, a bow support and fastener comprising a bow-supporting prop which is pivotally attached to one of said bows at the inner side thereof to swing to and from a 25 position lengthwise thereof, means for releasably holding the prop in said position, a stationary support, and means for releasably attaching the prop to said support for supporting the top when folded.
- 30 8. In combination with the bows of a folding vehicle top, and a stationary support for the bows when folded which extends outwardly from the vehicle to a point inside of said bows, a prop which is permanently secured to the rear bow of the top 35 and remains attached to the bow when the top is raised, and which has a part extending toward the vehicle from said bow and
- adapted to be secured to said support to hold said bow stationary when the top is folded.
9. In combination with the bows of a folding vehicle top, a bow support and fastener comprising a bow-supporting prop which is permanently attached to one of the bows and moves with said bow when folding and raising the top and is located between the bow and the vehicle when the top is folded, means for releasably fastening said prop to the vehicle for supporting the bows when the top is folded, and fastening means carried by and retained on one of the bows for securing the bows together when the top is folded.
10. In combination with the bows of a folding vehicle top, a bow support and fastener comprising a bow-supporting prop and co-operating bow fastening means both of which are carried by the top and are movable with the top when folding and raising the same and which are also movable relatively to each other for fastening the bows when the top is folded, and a part on the vehicle to which said prop is releasably secured for supporting the top in folded condition, said prop and bow fastening means being movable relatively to said bows to enable the same to be placed in comparatively inconspicuous positions on the bows when the top is raised.

Witness my hand this 19th day of December, 1916.

PETER BROADBOOKS.
